UNITED STATES PATENT OFFICE

111,824

DESIGN FOR AN EVENING WRAP

Lillian Zucker and Herman Feigenbaum,
New York, N. Y.

Application September 16, 1938, Serial No. 79,932

Term of patent 3½ years

To all whom it may concern:

Be it known that we, Lillian Zucker and Herman Feigenbaum, citizens of the United States of America, residing in the city of New York, county of New York, and State of New York, have invented a new, original, and ornamental Design for an Evening Wrap, of which the following is a specification, reference being had to the accompanying drawing, forming part thereof.

Fig. 1 is a front view of an evening wrap showing our new design.

Fig. 2 is a rear view thereof.

We claim:

The ornamental design for an evening wrap, substantially as shown.

LILLIAN ZUCKER.
HERMAN FEIGENBAUM.
